UNITED STATES PATENT OFFICE

127,700

DESIGN FOR A HOE HEAD OR SIMILAR ARTICLE

William Paschke, Faribault, Minn.

Application January 30, 1941, Serial No. 98,559

Term of patent 7 years

To all whom it may concern:

Be it known that I, William Paschke, a citizen of the United States, residing at Faribault, in the county of Rice and State of Minnesota, have invented a new, original, and ornamental Design for a Hoe Head or Similar Article, of which the following is a specification, reference being had to the accompanying drawing, forming part thereof.

I claim:

The ornamental design for a hoe head or similar article, as shown.

WILLIAM PASCHKE.
